SHOT SHELL

John M. Olin and Alfons G. Schuricht, Alton, Ill.,
assignors to Western Cartridge Company, East
Alton, Ill., a corporation of Delaware

Application January 28, 1931, Serial No. 511,669

5 Claims. (Cl. 93—94)

This invention relates generally to shot shells, and more particularly to tubes therefor, and the process and apparatus for making the same.

It is customary in the formation of tubes for shot shells to roll sheets of paper which have been covered with paste or other adhesive upon a mandrel so that the wall of the tube is composed of a number of convolutions of the paper. The paper alone, however, does not possess all the qualities which are required of a shot shell tube and accordingly, such tubes have heretofore been impregnated with paraffin, waxes or mixture of the two so as to waterproof the same and render them fireproof against the hot powder gases.

10 When the shell is fired, the hot powder gases moving outwardly through the shell wall dissipate their heat to the wax and transpose it from the solid state to the liquid, so that the latent heat of the wax is taken advantage of in

15 maintaining the temperature of the tube below the point of ignition, thereby preventing charring in the tube. Upon the explosion, however, the wax is liable to become cracked so that the powder gases are permitted to penetrate the pores of the paper following an irregular path, which results in a honeycomb structure, thereby weakening the tube to such an extent that it is incapable of withstand the force of the powder gases in the interior thereof, and, consequently,

20 the tube is liable to become ruptured.

Paraffin and other waxes being usually of a crystalline nature possess certain disadvantages which it is an object of this invention to overcome. Among the disadvantages of a crystalline material in this relation is the fact that the crystalline structure defeats the natural flexibility and pliability of the paper and reduces the entire shell to a structure more or less brittle and having substantially the same properties as the wax. It is, of course, well-known that when a shot shell is fired the tube must expand to meet the walls of the gun chamber, the paper alone not having sufficient strength to withstand the tremendous pressure of the gas generated during burning of the powder charge. Consequently, the treatment of such shot shell tubes with wax, although adequate to prevent the penetration of moisture and hot powder gases thru the wall of the tube, possesses the disadvantage of precluding such expansion of the tube upon firing the shell, which obviously will result in rupture to the tube and permit leakage of the powder gases, and thus interfere with the functioning of the gun.

Still another disadvantage in impregnating shot shell tubes with crystalline substances, such as waxes, is the fact that such waxes must be reduced to a substantially liquid form, requiring the application of considerable heat, before they can be successfully applied to the paper. It is well-known that paper when exposed to such temperatures as that of molten waxes, shows a substantial decrease in pliability, elasticity, and strength, and since in this particular use, it is necessary that the paper possess its maximum pliability, elasticity and strength, the use of such waxes as an impregnating substance is antagonistic to the good qualities of the paper employed. Furthermore, after the hot waxes have been applied to the paper a considerable contraction thereof takes place which has been found to set up internal stresses in the paper which increases the tendency toward rupture upon firing. Moreover since the characteristics of paraffin and other waxes are not such as to prevent the passage of gases, or in other words, the waxes are not entirely impervious to the passage of gases and, furthermore, since a number of fissures are liable to occur in a wax coating, upon cooling thereof, it has been found that such waxes are not as efficient in the prevention of the penetration of hot powder gases as is desirable. Accordingly, in such shells and tubes which have been impregnated with paraffin or another wax, it has been found that upon firing thereof the walls of the tube become punctured and thus permit the escape of gas as well as loss of firing pressure.

The object of this invention is, generally stated, to provide a material for the treatment of a shot shell tube paper which will not possess the disadvantages hereinbefore discussed.

Another object of the invention is to provide a shot shell tube having an inner layer of plastic substance.

Another object of this invention is to provide a process and apparatus for applying plastic substance to shot shell tube material during the process of forming the tube.

A further object of this invention is to provide a device for applying a coating of stearine pitch to the necessary area of the paper which goes to form the shot shell tube.

A more specific object of this invention is to provide a shot shell having a gas sealing medium in the wall thereof.

A further object is to provide a composite sheet of material for making shot shell tubes.

A further object is to provide a shot shell tube

having an isolated body of a gas sealing medium extending therearound.

Another object is to provide a shot shell tube having an elastic cooling medium in the wall thereof.

Other objects of this invention will become apparent to those skilled in the art when the following description is read in connection with the accompanying drawings thruout the various views of which like reference characters denote the same parts, and in which

Figure 1 is a view in side elevation of a shot shell tube formed in accordance with this invention;

15 Figure 2 is an enlarged detail view illustrating the disposition of a layer of plastic substance in the wall of a shot shell tube;

Figure 3 is a plan view of a sheet of tube forming material having a portion thereof covered 20 with a plastic substance in accordance with this invention;

Figure 4 is a view of the sheet illustrated in Fig. 3 after being rolled to form a tube;

Figure 5 is a sectional view in side elevation of 25 a machine for coating the sheets as illustrated in Fig. 3;

Figure 6 is a plan view of the machine illustrated in Fig. 5;

Figure 7 is a plan view of a modified form of a 30 machine for coating sheets as illustrated in Fig. 3;

Figure 8 is an end elevation of the machine illustrated in Fig. 7;

35 Figures 9 to 13 inclusive, are diagrammatic illustrations of modified means for carrying out the process of this invention.

This invention contemplates the provision of a gas sealing medium in the wall of the shot shell tube. The criterion for such a medium would, of course, be a wall of liquid, such as, for instance, 40 water between successive convolutions of the tube forming material. Since, however, such a liquid cannot be practically employed for this purpose it has been found that any suitable plastic substance such as a pitch, is adaptable for this use.

In accordance with this invention a plastic substance which may be, for instance stearine pitch, is applied to the paper or material which goes to form a tube of the shot shell. A plastic substance, 50 such as for instance stearine pitch, possesses all the advantageous qualities necessary for rendering the tube more impervious to moisture and hot powder gases. Moreover such a plastic substance does not in any way affect the physical characteristics of the paper or other material of which the tube is formed. It may be preferable to dissolve the plastic substance such as stearine pitch in a suitable solvent and apply the solution to the paper to be thus treated and thus coating the same. Of course, any suitable solvent may be employed, for instance carbon tetrachloride, benzol, naphtha, etc., but for the purpose of illustration carbon tetrachloride will be used. Such a solution lends itself to application by means of 55 a number of different types of apparatus, such as for instance by rolling, brushing, spraying or stamping. It is often preferable, however, to apply the stearine pitch without the use of such a solvent and in this case it becomes necessary to heat the pitch slightly above normal temperature under which circumstances it becomes of high viscosity and is readily applicable. In this form, however, the stearine pitch is most readily applied to the tube forming material by rolling.

70 75 It is not necessary to coat the entire sheet of

material which goes to form the tube of the shot shell since if there exists a layer substance which extends completely about the circumference of the tube, this will be sufficient to prevent the penetration of moisture as well as the passage of hot powder gases. For this reason it has been deemed preferable to apply the stearine pitch only to such portion of the strip of tube forming paper or other material as will be necessary to form one complete convolution within the tube. The pitch-covered convolution is preferably disposed near the inner wall of the tube and for this reason the tube forming material should take one complete convolution before that portion carrying the stearine pitch is wound thereupon. Thus since in shot shell tubes a number of convolutions of material are required to form the completed tube, there will exist uncoated convolutions of material on both sides of the coated convolution in a shell constructed in strict accordance with this invention. It is, nevertheless, within the scope of this invention to completely cover or thoroughly impregnate the entire strip of material which goes to form all the convolutions of such a shot shell tube.

It is apparent that such a plastic substance as stearine pitch may be readily applied to the paper or other material for forming the shot shell tube at any time prior to the rolling process thereof. This invention, however, contemplates the application of such stearine pitch to the tube forming material by the provision of a pitch applying device upon the tube forming machines as heretofore known.

Referring now to the drawings, and particularly to Figs. 1 and 2 thereof, it will be observed that the shot shell of this invention comprises a plurality of convolutions 1 of tube forming material, such as paper, as clearly illustrated in Fig. 2. Between successive convolutions 1 and the inner wall of the tube a layer of plastic substance 2, such as for instance stearine pitch, is provided to prevent the penetration of moisture and render the tube impervious to hot powder gases. It will be understood that the layer 2 of stearine pitch extends completely about the circumference of the tube and preferably is lapped upon itself for a short distance to insure the seal.

In the process of rolling shot shell tubes as heretofore known it has commonly been the practice to roll a sheet of tube forming material, such as paper, having a width equal to the combined circumference of the plurality of convolutions which go to form the finished tube, and a length equal to the length of a plurality of finished shot shell tubes. Referring to Figs. 3 and 4, it will be observed that a sheet of paper 3 is of substantially rectangular form, the width dimension $a-b$ thereof being equal to the length of the strip of material embodying the tube of the shot shell illustrated in Fig. 1 as if the same were unrolled. For the purpose of illustration, the length $b-c$ of the sheet of paper 3 is equal to the combined length of five such shot shell tubes as illustrated in Fig. 1 as is clearly seen from Fig. 4. It is thus apparent that when the sheet 3 is rolled into tubular form it may be readily sub-divided to form any desired number of finished shot shell tubes. Thus on the sheet of paper 3 a portion thereof, having a width $d-e$ substantially equal to be preferably slightly in excess of circumference of the finished tube, is given an application of stearine pitch or other plastic substance. It is, of course, apparent from Fig. 3 that the area covered by the stearine pitch extends completely 70 75

across the sheet of paper 3, it may here be pointed out, however, that the application may be made to a plurality of areas having lengths substantially equal to the length of the powder and shot 5 charge to be placed in a completed shot shell. Under the latter circumstances a space would exist between adjacent areas having an application of stearine pitch intermediate of which space the tube would be sub-divided to form the smaller 10 tube of the finished size.

In carrying out the tube forming process in accordance with this invention, a tube rolling machine built and constructed in accordance with the prior art such as illustrated in Figs. 5 and 6 15 may be employed. Such a tube rolling machine comprises a table 4 for receiving and guiding the paper or other material to be rolled into tubes. A feeding arm 5 is translatable back and forth across the table 4 to feed such sheets of paper 20 as 3 to the rolling machinery in predetermined regularity. In accordance with the prior art, the feeding arm 5 forces the sheet of paper 3 toward the rolls 6 and 7. The rolls 6 and 7 are mounted in vertical alinement, the former being 25 biased toward the latter by spring 8 to effect a continuous positive engagement between the surfaces of the two rolls. The roll 7 is driven in a counter-clockwise direction and the roll 6 in a clockwise direction so that when the forward edge 30 of the sheet material 3 is projected between the rolls it will be drawn forward thereby and advanced to a mandrel 9 which operates to wind the sheet into a tube as is well known in the art. Disposed beneath the roll 7 is a receptacle 11 35 adapted to contain a quantity of suitable adhesive, such as for instance paste, whereby it is possible to transmit a coating of such adhesive to the sheet of paper when it passes thru the rolls 6 and 7. It is, of course, understood that 40 the mechanism comprising the feeding arm 5, the rolls 6 and 7, and the mandrel 9 are driven from a unitary source of power, being directly connected so that they operate in a fixed time relation. For instance it will be observed that 45 the roll 7 is provided with an elevated concentric portion 12 of a circumferential length substantially equal to the width of the sheet of paper 3 and the arm 5 preferably operates in such timed relation with the rolls that the forward edge of a 50 sheet of paper is projected between the rolls 6 and 7 just prior to the time when the forward edge of the elevated concentric surface 12 comes into contact with the roll 6. The elevated concentric surface 12 when in engagement with the roll 55 6 causes the spring 8 to thus increase the pressure between the rolls which in effect positively grips the sheet of paper which is passing therebetween at that particular time. The sheet of paper thus positively gripped is fed on toward 60 the rotating mandrel 9 which picks up the forward edge thereof in cooperation with a pick-up 13 to roll the sheet into a tube in a manner well known in the art. It is understood that the structure just described is strictly in accordance with 65 the prior art.

The present invention contemplates the provision of a device for applying stearine pitch to the sheet of paper 3 during the operation of the rolling machine previously described. An illustrative embodiment of such a stearine applying device is illustrated in Figs. 5 and 6 wherein it 70 will be observed that a pair of upright members 14 are provided on opposite sides of the table 4 to provide a suitable support for the mechanism now to be described. Extending between the

members 14 is a receptacle 15 adapted to contain a quantity of stearine pitch. The receptacle 15 is provided with a lower closed compartment 16 for containing an electric heating element so that sufficient heat may be applied to the receptacle 5 15 to reduce the stearine pitch to a molten condition. A roll 17 has its opposite ends journaled for rotation in the upright members 14 and is disposed directly above the receptacle 15 in such position that a substantial portion of its surface 10 is immersed in the molten stearine pitch contained in the receptacle 15. The roll 17 is provided with an absorbent surface 18 of any suitable material such as is well known in the art. Another roll 19 having a similar absorbent surface 15 18 is journaled between the upright members 14 for rotation tangent to the roll 17 and it is thus apparent that stearine pitch attaches itself to the absorbent surface 18 of the roll 17 whereby it will be transferred upon rotation 20 thereof to the absorbent surfaces of the roll 19. A third roll 21 is mounted for rotation between the upright members 14 and is provided with an elevated concentric surface 22 having an absorbent material thereon. As is clearly illustrated in 25 Figure 6 the rolls 19 and 21 are positively driven thru gear train 23, 24, 25, directly from the feeding and pasting rolls 6 and 7. It is thus apparent that the roll 21 operates in the same fixed time 30 relation which exists between the operation of the feeding arm 5 and the rolls 6 and 7 so that the roll 21 makes one complete revolution for every sheet of paper which passes thereby and thereunder. It is preferable that the peripheral area 35 of the elevated concentric portion 22 be equal to the area over which it is desired to apply the stearine pitch to the sheet of paper 3. Thus the peripheral length of the elevated concentric portion 22 is equal to the distance $d-e$ as indicated in Fig. 3, and it is, of course, understood that 40 the elevated concentric portion 22 extends the entire length of the roll 21. The roll 21 is journaled in such position that the surface of the elevated concentric portion 22 becomes successively tangent to the surface of the roll 19 and 45 the surface of a pressure roll 26, the latter of which is disposed in which position that the plane of the top surface of the table 4 is tangent thereto. The advancing sheet of paper 3 is thus gripped between the surface of the elevated concentric portion 22 of roll 21 and the surface of roll 26, after the forward edge of the paper has 50 passed thereby as is clearly shown in Fig. 5, and the surface of the elevated concentric portion 22 having received a supply of stearine pitch from 55 the roll 19 transfers a quantity of such pitch to the paper passing therewith so that the surface of the paper illustrated in Fig. 3 is partially covered with a coating of pitch. The forward end of the sheet 3 moves beneath a stripper 27 60 disposed in such a position that it prevents the paper from sticking to the surface 22 during continued movement of the latter.

The sheet of paper 3 is then drawn forwardly, 65 after having the desired surface covered with stearine pitch by surface 22 of roll 21 and gripped between the rolls 6 and 7. Here a coating of a suitable adhesive, such as for instance, paste, is applied to the sheet and it is advanced on to 70 the revolving mandrel 9 where it is wound into tubular form such as shown in Figure 4.

A modified form of a device for applying stearine pitch to the paper is illustrated in Figures 7 and 8 and it may be pointed out that the em- 75

bodiment there illustrated may be substituted for the pitch applying mechanism illustrated in Figures 6 and 7 to operate in the same regular timed relation with the mechanism of the tube rolling machine. In the embodiment illustrated in Figures 7 and 8, the coating of stearine pitch is applied to the bottom surface of the sheet of paper and for this reason it becomes necessary to provide this embodiment in such a position that the sheet may be inverted before being engaged by the feeding arm 5. Such mechanism as is necessary to invert the sheet of paper are well known in the art and are accordingly not shown in the drawings. In the embodiment illustrated in Figures 7 and 8 a suitable receptacle 28 is provided for containing the stearine pitch which, like the receptacle 15, may or may not be provided with a heating element as is desired. Disposed so that the plane of table 4 is substantially tangent to the surface thereof is a drum 29. The drum 29 is so disposed that the surface thereof is immersed in the stearine pitch contained in the receptacle 28 upon rotation thereof. The roll 29 is rigidly mounted upon shaft 31 which may be journaled in suitable bearings at opposite sides of the table 4 and is rotatable therewith. It may be pointed out, however, that the drum 29 may be adjusted axially of the shaft 31 to vary the position of the surface of the sheet to be coated relative to the dimensions of the sheet. In this embodiment the width of the roll 29 is equal to the width of the area of stearine pitch applied to the sheet of paper 3 and suitable means is provided to remove the stearine pitch deposited upon the periphery of the drum 29 from the surface thereof, except for a peripheral distance equal to the length $b-c$ as shown in Fig. 3.

The means for preventing the transfer of stearine pitch by said portion of the periphery of the drum 29 includes a pair of cams 32 mounted upon opposite ends of the shaft 31 and rotatable therewith. The cams 32 at opposite ends of shaft 31 are similarly disposed relative to the shaft and each have a portion of constant radius extending counter-clockwise from f to g . The portions thereof which exist in the clockwise direction between f and g being of lesser radius (as seen in Fig. 8). A pair of arms 33 are pivoted at opposite sides of the table 4 and are each provided with an arm 34 extending in the direction of cam 32. On the outer end of arm 34 is provided a follower wheel 35 disposed for engagement with the peripheral surface of the cam 32. Springs 36 are provided which normally bias the arms 33 toward the cam 32. A scraper plate 37 is mounted upon the arms 33 and extends beneath the table 4 across the entire width thereof and in close proximity to the surface of the drum 29. It is apparent that when the parts are in the position shown, the stripper 27 is held out of contact with the surface of the roll 29, however, it is apparent that upon clockwise rotation of the drum 29 the scraper 37 will come into engagement with the surface of the drum 29 between positions g and f , it being apparent that between these positions the follower 35 will be permitted to move toward the right under the action 36 to bring the scraper into contact with the drum 29 as described.

The surface of the drum 29 is provided with a recess or indentation 38 which lies within the area from which the pitch is removed by the scraper but near to the end thereof. The indentation 38 is disposed to accommodate the forward edge of a sheet of paper 3 to facilitate the starting of the same between the surface of roll 29

and the surface of the pressure roll 39 in contact therewith. It is thus apparent that the forward edge of the sheet of paper is gripped between the rolls 29 and 39 and advanced for a short distance before the application of stearine pitch begins. Upon forward movement of the roll 29 in the clockwise direction the sheet 3 will be drawn toward the right and forced between the rolls 29 and 39, the former of which will deliver the application of stearine pitch to the under surface of the sheet, until the point g on the surface thereof is reached. When the point g is reached the scraper 37 is then released by the action of cam 32 and follower 35 to remove the pitch from the remaining surface. This operation is repeated for each sheet passed therethru.

As heretofore pointed out the process of applying stearine pitch to sheets of shot shell tube material before the rolling may be carried out by various means. In Figs. 9 and 10 a device is illustrated which combines the features of that shown in the preferred embodiment, Figs. 5 and 6, and that shown in Figs. 7 and 8. In the embodiment shown in Figs. 9 and 10 the roll 41 thereof is of a width equal to the width of the area to which it is desired to apply the pitch, i. e., $d-e$ of Fig. 3. This particular embodiment is readily adaptable to the process when the tube material is taken from a roll. With this arrangement, it is thus possible to continuously draw a long strip of paper or other tube material beneath the roll 41 and apply thereto an application of stearine pitch of the desired width. The strip of paper may subsequently be cut into sheets of the desired length for handling by the customary tube rolling machine.

In Figures 11 and 12 a further modification is shown in which a spray 42 is moved across the paper to be treated to deliver a desired application of stearine pitch. In this embodiment the member 42 is preferably of a width $d-e$ corresponding to the width of the area to which the pitch is applied upon the sheet of paper. The member 42 is oscillated lengthwise of the sheet of paper by any suitable oscillating mechanism, such as a cross head 43 and linkage 44. It is further possible to provide upon the member 42 a number of bristles in order to spread the stearine pitch more evenly across the surface of the paper.

In the embodiment illustrated in Fig. 13 the pitch is applied to the paper by a stamping process. In this embodiment a stamping machine is provided with a head 45 of the same dimension as the area of the paper to be covered and is oscillatable by any suitable mechanism, such as a linkage 46 between a position in which it engages a pad 47 to receive a supply of the pitch and another position in which it is impressed upon the paper to deliver thereto an application of pitch. It may be pointed out that this particular embodiment may be substituted for the feeding arm 5 of the ordinary tube rolling machine since it is readily possible to arrange the head 45 so that it may be moved thru a sufficient amplitude in engagement with the paper 3 to advance the same as has heretofore been accomplished by feeding arm 5.

It is to be understood that this invention is not limited to the use of stearine pitch as a gas sealing medium, and that many other substances such as, for instance, asphaltum, and other pitch like compositions, which are preferably elastic in their nature and possess elasticity, may be employed as the gas sealing medium. It is to be

understood, however, that it is preferable to employ some substance which will perform the same function as the waxes, as heretofore used, in cooling the tube upon penetration of the hot powder gases. This result may, however, be accomplished not only by taking advantage of the latent heat of the gas sealing medium, but also in substances which have a higher specific heat than paper the same result will be accomplished, since the tube is maintained at a temperature below the ignition point.

As another embodiment of this invention, a sheet of tube forming material of a thickness less than that usually employed may be first coated with the gas sealing substance such as stearine pitch and after the application thereof, another thin sheet of material may be applied over the film of stearine pitch so that a composite sheet results, the thickness of which is preferably the same as the single sheets employed in the embodiments of this invention hereinbefore described. Furthermore, the stearine pitch may be initially applied to a thin sheet of paper and the film subsequently covered over by another thin sheet so that in effect a paper tube is formed having on the interior thereof a film of the gas sealing medium. This flat tube containing the gas sealing medium may then be laid on the sheet of tube forming material just prior to the rolling process thereof as an inlay, substantially in the same manner as that described in our copending application Serial No. 511,668, filed January 28, 1931, for inserting a metallic strip in the wall of a shot shell tube. By this latter process, it is apparent that an isolated body of the gas sealing medium is provided between the convolutions of the paper, and as described with reference to the preferred embodiments of this invention, the film of gas sealing substance preferably extends for the full circumference of the tube with a slight overlap.

Thus in accordance with this invention a sheet of tube forming material, after having been coated with a suitable plastic substance such as stearine pitch, is rolled into tube form and in accordance with general practice is of such length as to form a plurality of sized shot shell tubes. Accordingly the tube, after having been rolled upon a mandrel, such as 9, is sub-divided into a plurality of tubes of the desired length, each having therein a complete convolution of a gas sealing medium. After the tubes have been sized, it is desirable that they be given a coating of water proofing material, such as for instance a nitro-cellulose lacquer, the function of which is to prevent the entrance of moisture through the outer convolutions of the tube forming material of the tube.

It is thus apparent that the various modifica-

tions shown and described are each capable of being used in conjunction with the customary tube rolling machine for carrying out the process of this invention, but since it is apparent that many other modifications will present themselves to those skilled in the art and which may be readily adaptable for carrying out the process of this invention, it is to be distinctly understood that the embodiments here shown and described are merely illustrative and shall not be construed in a limiting sense. 10

While stearine pitch is particularly suitable and efficient to provide a seal between the convolutions of a paper shell tube, it will be understood that other pitches and other plastic substances having the desired characteristics, may be employed to attain, to an extent at least, the objects and purposes of this invention. It is to be understood that the term "stearine pitch" and even the term "paper" are used in a descriptive 20 and not in a limitative sense.

Since it is possible for the process and product of this invention to be modified without departing from the spirit of the invention, it is to be distinctly understood that such modifications and the use of sub-processes which, although not specifically described herein, are contemplated by and within the scope of the appended claims.

It is to be further understood that the foregoing description and the accompanying drawings are merely illustrative of the preferred embodiment of the process and apparatus of this invention and shall not be construed in a limiting sense.

Having thus described the invention what is claimed is:

1. A shot shell having a tube composed of convolutions, one of said convolutions being coated with stearine pitch.

2. A shot shell having a tube composed of convolutions of paper with stearine pitch between convolutions.

3. A shot shell having a tube containing a non-penetrating gas-sealing medium in the wall thereof, said medium remaining sufficiently plastic to permit the tube to expand under the force of firing.

4. A shot shell having a tube composed of convolutions of paper, one of said convolutions being coated with a nonpenetrating gas-sealing medium in the wall thereof, said medium remaining sufficiently plastic to permit the tube to expand under the force of firing.

5. A shot shell tube composed of convolutions of paper, one of said convolutions being coated with a layer of asphaltum.

JOHN M. OLIN.
ALFONS G. SCHURICHT.
